CARTON STAPLING MACHINE

Joseph Mason Kirton, Bountiful, Utah

Application January 26, 1959, Serial No. 54,325

Term of patent 7 years

(Cl. D74—1)

FIG. 1

FIG. 2

FIG. 3

The left side of the machine is substantially identical to its right side, shown in Figure 2.

I claim:

The ornamental design for a carton stapling machine, substantially as shown and described.
